Held, Bronx, N.Y.; said Faust and said Held assignors, by mesne assignments, to Olin Mathieson Chemical Corporation, a corporation of Virginia, and said Gould assignor, by mesne assignments, to Thiokol Chemical Corporation, a corporation of Delaware
No Drawing. Filed May 21, 1956, Ser. No. 586,327
2 Claims. (Cl. 204—157)

This invention relates to the conversion of diborane to higher boron hydrides. More particularly it relates to the conversion of diborane to higher boron hydrides employing gamma radiation.

The higher boron hydrides such as tetraborane and pentaborane are useful as welding fuels, as described in U.S. Patent 8,582,268, and for other purposes.

It has now been found that tetraborane and other higher boron hydrides can be obtained by subjecting diborane to gamma radiation. Thus according to the present invention, diborane at a temperature of about 0° to 40° C. is subjected to a source of gamma radiation of suitable intensity and for sufficient time to provide a total radiation of about 1 to 50 million roentgens. A total radiation of less than about one million roentgens at temperatures in the vicinity of 0° C. provides little conversion while higher total radiations at higher temperatures provides conversions of diborane to higher boron hydrides of 4 to 6% or even higher.

Any suitable source of gamma radiation can be used in the process of this invention. Cobalt-60 is a particularly convenient source of suitable intensity and is readily available by the radiation of ordinary cobalt in an atomic reactor. Tantalum-182 is another suitable gamma radiation source. Mixed elements from an atomic reactor, designated as "hot fuel elements," containing various radioactive isotopes formed when either uranium or plutonium undergo fission, can be used. The fission products can be used as such or may be partially or completely separated into radioisotopes. Direct gamma radiation, which can be mixed with neutrons, is also useful for the purposes of the present invention. The presence of beta rays in the gamma rays does not appear to be deleterious although the beta radiation appears to be inactive in effecting chemical conversions because of its low penetration.

The cobalt-60 source of gamma radiation is particularly convenient and accessible. It has a half life of about 5.1 years and the hard gamma radiation therefrom comprises rays of 1.17 mev. (millielectron volts) and 1.34 mev. in cascade. The cobalt-60 source can be in any suitable form and arranged in any desired manner. For example, it can comprise pellets about 1 centimeter in diameter by 1 centimeter in length embedded in the end of a steel or lead piston. Alternatively, the cobalt-60 source can be in cylindrical form. In use the radiation source is provided with suitable shields for the protection of personnel which still allow irradiation of the sample. Lead is a particularly suitable shield material and a thickness of 8 to 10 inches in all directions from the radiation source appears to be sufficient to provide adequate protection.

The cobalt-60 source can vary in intensity, for example, it can be 300 or 400 curie material. Cobalt sources of greater or lesser intensity can be used and the time of exposure adjusted accordingly to provide adequate dosage.

Where desired, gaseous diluents may be used with the primary reactants. For this purpose, argon or helium are preferred, although nitrogen or hydrogen may be used.

The use of somewhat elevated pressures is usually desir-

2

able for the most advantageous results although, for some purposes, the use of atmospheric or subatmospheric pressures may be desirable. The use of about 2 to 20 atmospheres pressure is particularly advantageous.

The sample of the material to be treated is contained in a stainless steel or other suitable metallic reactor. It may be desirable, particularly where solid or liquid products are formed, to use a glass or other suitable liner for such metallic containers. The design and material of the container will depend in large part on the pressure to be used or developed during the irradiation.

No significant temperature effect occurs during the irradiation and usually the large bulk of shielding material serves to maintain the reaction mixture at substantially constant temperature. Where desired, suitable means of heating or refrigeration can be arranged to maintain constant temperature conditions. The irradiation can be carried out at reduced or elevated temperatures, for example, from -40° C. to 100° C. or more.

In the following examples, a cobalt-60 radiation source which had a strength of approximately 400 curies was used. It consisted of a hollow cylinder approximately 13 1/4 inches in length by 2.3 inches outside diameter and 1.7 inches inside diameter. The cobalt was encased in a stainless steel shell and surrounded by cooling coils packed in thermal insulating material. The whole assembly had a diameter of approximately 5 inches and was placed in a lead pig. The pig was a cylinder with a central core 5 inches in diameter and a wall thickness of 8 inches. The lead pig also had a base 8 inches thick below the cobalt cylinder. The upper portion of the lead pig serving as a lid consisted of three inches of lead and 7 inches of steel. Using this source and geometry of equipment, the average dose in the irradiation region was 150,000 roentgens per hour (one roentgen is equivalent to 93 ergs per gram).

Example I

A stainless steel bottle about 1.5 inches in diameter and 12 inches in length having a capacity of 150 ml. and fitted with suitable valve inlets was thoroughly washed with detergents and water, rinsed thoroughly with water and evacuated while heating to 60-80° C. The clean, dry cylinder was connected to a vacuum manifold and evacuated to a few microns pressure. The evacuated system was checked for leaks by standing for several hours and observing the pressure. If the system was not tight the above procedure was repeated. When the system was tight, diborane was introduced into the manifold and condensed into the irradiation cylinder by maintaining the latter at liquid nitrogen temperature. The valves on the irradiation cylinder were closed and the bomb removed from the manifold and transferred to the irradiation chamber described above. The charge was 78.4 millimoles of diborane. At atmospheric temperature, the pressure was about ten atmospheres.

The bottle containing the diborane was introduced into the irradiation assembly and exposed to gamma radiation at a dosage rate of 150,000 roentgens per hour for 24 hours. This amounts to a total dosage of 3,600,000 roentgens. During the treatment the irradiation cylinder and contents were maintained at -2° C. The irradiation cylinder and contents were removed from the irradiation chamber and chilled with liquid nitrogen. Uncondensed hydrogen was removed with a Toepler pump to a calibrated bulb. The irradiation cylinder was then warmed and a small sample of gas transferred to an evacuated infrared cell and analyzed. These analyses showed the formation of 0.5 millimole of hydrogen and the residual gas from the removal of hydrogen contained 3.2 mole percent of tetraborane corresponding to a conversion of about 6.2 percent of the diborane charged.

By fractional condensation the tetraborane can be recovered and unreacted diborane recycled for additional treatment.

Example II

An irradiation cylinder cleaned as described in Example I was charged with 75.8 millimoles of diborane and irradiated as described in Example I but at 25° C. for 168 hours. The total exposure amounted to 25.2 million roentgens. Infrared analysis of the product mixture indicated that it contained 95.1 percent of the boron in the form of diborane, 4.0 percent in the form of tetraborane, 0.83 percent in the form of pentaborane(11) and 0.08 percent in the form of solids. This corresponds to a conversion of about 4 percent of the charged diborane to tetraborane.

The products can be readily separated by fractional condensation and the unreacted diborane recycled for further treatment.

Other useful interconversions of boron hydrides are effected according to the present invention by irradiation with gamma rays. For example, the method can also be applied to the further irradiation of tetraborane, the irradiation of pentaborane(9), pentaborane(11), decaborane, or of the yellow solids produced by pyrolysis of lower boron hydrides. Organic derivatives of the hypothetical BH_3 can be irradiated, for example, trimethylborane, triethylborane, triisobutylborane and higher homologues. To obtain useful products it is not necessary to use individual compounds as starting materials, for example, mixtures of boron hydrides can be used. A mixture of diborane and tetraborane is a suitable starting material as well as mixtures of diborane with pentaborane(9), pentaborane(11), and trialkylboranes. Reactions of boron hydrides with other materials can also be effected using gamma radiation. Thus, a mixture of diborane with ethylene or other olefinic or acetylenic materials with various boron hydrides can be treated. Propylene, butene-1, butene-2 and 2-methylpropene-1 or mixtures of such olefins with boron hydrides can be irradiated according to the process of the present invention. Acetylene, methylacetylene, allene, butadiene - 1,3, 2-

methylbutadiene-1,3 and other unsaturates admixed with boron hydrides can be irradiated. In some cases hydrogen can additionally be introduced, particularly in the treatment of the yellow solids obtained by pyrolysis of lower boron hydrides. Thus mixtures of hydrogen and yellow solids can be irradiated. Olefins or acetylenes, for example, ethylene or acetylene itself can be incorporated in such mixtures and subjected to gamma radiation. Alkyl borohydrides, for example, ethyldecarborane or ethylpentaborane can be treated in admixture with diborane. The method is also useful for the hydrogenation of borate esters, for example, trimethylborate, for the hydrogenation of mixtures of boron halides and alkali or alkaline earth metals, including magnesium, to form boron hydrides and for the hydrogenation of metal borides, for example, ferric boride or calcium hexaboride or for the hydrogenation of boron carbides, for example, B_4C .

We claim:

- 20 1. A process for the conversion of diborane to a product mixture containing tetraborane and other higher boron hydrides which comprises subjecting the diborane at a temperature of about 0° to 40° C. to a source of gamma radiation of suitable intensity and for a sufficient time to provide a total radiation of about 1 to 50 million roentgens.
- 25 2. The process of claim 1 in which the source of gamma radiation is cobalt-60.
